(57) **CLAIM**

The ornamental design for a motorcycle exhaust end cap, as shown and described.

DESCRIPTION

FIG. 1 is a front elevational view in perspective, showing the front of the motorcycle exhaust end cap of the present invention;

FIG. 2 is a top view in perspective thereof;

FIG. 3 is a side view thereof, the opposite side being identical thereto; and,

FIG. 4 is a bottom view in perspective of a motorcycle exhaust end cap.

The broken line showing of environment is for illustrative purposes only and forms no part of the claimed design.
